ILLINOIS.

DRAWBAR.

1,421,032.

Specification of Letters Patent. Patented June 27, 1922.

Application filed April 2, 1920. Serial No. 370,668.

To all whom it may concern:

Be it known that we, GEORGE N. SIMPSON, ARTHUR M. SIMPSON, and WALTER H. SIMPSON, citizens of the United States, residing at Chicago, in the county of Cook and the State of Illinois, have invented new and useful Improvements in Drawbars, of which the following is a specification.

This invention relates to improvements in drawbars and more especially to a drawbar of the swivel type.

In the use of rotary dumps, tilting dumps, and other appliances where one or more cars in a train are dumped or tilted without uncoupling them from the rest of the cars in the train, it is necessary to provide a swivel drawbar to permit the necessary rotation of the cars being dumped without injuring the couplings. Swivel drawbars of various types have been made and used heretofore. In the use of such drawbars difficulty has been encountered in providing means to cause the drawbars themselves to tend to assume a normal horizontal position when no rotation is taking place. It is desirable that there be this tendency so that when the cars are in their normal upright position, the drawbars will lie in their normal horizontal position to permit coupling and uncoupling. Heretofore swivel drawbars have been made with locks to hold them in a horizontal position. In the use of such drawbars it is necessary to disengage the lock manually or by other means to permit rotation. If the releasing means should fail to work, serious damage would result when an attempt is made to rotate one of the cars coupled to another car standing on a stationary track.

We have designed a swivel drawbar which is always freely rotatable, and which always tends to assume a normal horizontal position when the car to which it is attached is not actually being rotated.

In general, we have accomplished the features of our invention by providing a drawbar with its head below the center or axis of the drawbar shank so that if the drawbar head is turned, the center of gravity is raised. In addition, the drawbar shank is elliptical in cross section so that any turning of the drawbar head from its normal horizontal position will raise the center of gravity of the head a greater distance than if the drawbar shank were circular in cross section.

The features above mentioned and others of our invention will appear more clearly as we proceed with our specification.

In that form of device embodying our invention, shown in the accompanying drawings:

Figure 1 is a top plan view of our improved drawbar.

Figure 2 is a vertical sectional view on the line 2, 2 of Fig. 1.

Figure 3 is a longitudinal sectional view on the line 3, 3 of Fig. 1.

Figure 4 is a vertical sectional view on the line 4, 4 of Fig. 3.

Figure 5 is a vertical sectional view on the line 5, 5 of Fig. 3.

As shown in said drawings, A indicates, in general, the drawbar head and B the shank. C indicates, in general, a housing or support for the shank B.

The head A is bifurcated as shown in Fig. 3, providing a wide flat upper prong 1 and wide flat lower prong 2. A vertical cylindrical hole 3 is provided through the two prongs 1 and 2 for the purpose of accommodating a pin (not shown) adapted to attach the head A to a complementary member on another car (not shown). As shown in Figures 1 and 2 the drawbar head A is in its normal horizontal, or upright position. It is one of the objects of the present invention to provide means for causing the drawbar head to tend at all times to assume this position; since this position is necessary to permit coupling and uncoupling.

The shank B at its extreme inner end is circular in cross section (see Fig. 4). As it approaches the drawbar head A it becomes more and more elliptical in cross section, with the longer axis horizontal (see Fig. 2).

The shank B is hollowed out as indicated by 5, the hollow portion being made smaller near the end of the shank to provide the shoulder 7.

The following means are provided for supporting the drawbar shank B. 8, 8 indicates the ends of two channel irons extending from the car (not shown). Supported between the two channel irons 8 by means of the bolts 10, 10 is the casting or housing C with its outer end provided with a hole 15. The hole 15 at its inner end 16 is circular in cross section and slightly larger than the inner end of the shank B. As the hole 15 approaches the outer end of the

housing C it is enlarged and made oval in cross section as shown in Fig. 2, with its large curve below and its small curve above. The hole 15 and the housing C are provided 5 for the purpose of accommodating the shank B, the enlargement and oval shape at its outer end being provided for the purpose of permitting rotation of the elliptical shaped shank.

10 It will be noted that the lower prong 2 of the drawbar head A is a greater distance below the axis of rotation of the shank B than the upper prong 1 of the head A is above such axis of rotation. It is obvious from 15 this construction that the center of gravity of the drawbar head is below the axis of rotation of the drawbar shank, and that if the drawbar head is turned the center of gravity will be raised. It will be noted also 20 from Fig. 2, that, due to the elliptical shape of the drawbar shank B, the center of gravity of the head, when the drawbar is turned, will be raised a greater distance than if the shank were round. This is due to the 25 fact that such rotation will cause the ellipse to be rolled up on its long axis.

The following means are provided for holding the drawbar shank B in the hole 15, for absorbing any shocks against the 30 head A, and for permitting rotation of such head. A long bolt 17 with its head 18 in the hole 15 in the shank B resting on the washer 19 which in turn lies on the shoulder 7, extends entirely through the housing C and 35 has keyed to its end by means of the key 20, a sleeve 21 with a flange 22 lying inside of a recess 23 provided in the housing C around the hole 15. Lying within the recess 23 is another sleeve 25 with a flange 27 40 at the forward end of the recess 23. Encircling the bolt 17 and the sleeve 25 is a spiral compression spring 29 with one end bearing against the flange 27 and the other against the flange 22. The length and tension of the spiral spring acts normally to 45 hold the flange 27 against the forward end of the recess 23 and the flange 22 against the rear end of the recess 23 in the positions shown in Fig. 3. The sleeve 25 is of proper 50 length to permit the flange 27 to be pushed backward by the shank B to compress the spring 29 when sufficient pressure is borne against the drawbar head. By means of this construction any shock or bump against 55 the drawbar head A tending to force it inwardly will be absorbed by such compression of the spring. In a similar manner a quick jerk or pull on the drawbar head A will 60 be absorbed by the flange 22 moving outwardly and compressing the spring 29.

We claim:

1. In combination with a car adapted to be dumped by rotation without uncoupling it from adjoining cars in a train, means on the car for coupling it to an adjoining car, 65 said means comprising a draw-bar support on the car, and a draw-bar rotatably mounted in the support, the shank of said draw-bar where supported in the support being substantially elliptical in cross section. 70

2. In combination with a car adapted to be dumped by rotation without uncoupling it from adjoining cars in a train, means on the car for coupling it to an adjoining car, 75 said means comprising a draw-bar support on the car, and a draw-bar rotatably mounted in the support, said draw-bar having its shank where supported in the support substantially elliptical in cross section and having a coupling head on its end, the center of gravity of said head lying below the axis of rotation of the shank. 80

3. In a device of the character described, a draw-bar support, and a draw-bar swivelly mounted in the support, the shank of said draw-bar where supported in the support being substantially elliptical in cross section. 85

4. In a device of the character described, a draw-bar support, and a draw-bar rotatably mounted in the support, said draw-bar having its shank where supported in the support substantially elliptical in cross section and having a coupling head on its end, the center of gravity of said head lying below the axis of rotation of the shank. 90

5. In a device of the character described, a draw-bar support, and a draw-bar rotatably mounted in the support in such a manner that rotation of the draw-bar from its normal position will raise the center of gravity thereof and also raise the axis of rotation. 95

6. In a device of the character described, a draw-bar support, and a draw-bar rotatably mounted in the support in such a manner that rotation of the draw-bar will raise the axis of rotation thereof. 100

7. In a device of the character described, a draw-bar support, and a draw-bar rotatably mounted in the support in such a manner that contact between the draw-bar and the support upon rotation of the draw-bar therein will raise the center of gravity of the draw-bar. 110

In witness whereof, we have hereunto subscribed our names this 23d day of March, 115 1920.

GEORGE N. SIMPSON.
